SWITCHING DEVICE

Fredric E. Wood, Oak Park, Ill., assignor to
Associated Electric Laboratories, Inc., Chicago,
Ill., a corporation of Delaware

Application April 24, 1939, Serial No. 269,689

11 Claims. (Cl. 200—1)

The present invention relates to switching devices and, more particularly, to electrical switch devices of the electromagnetic relay type.

A switching device of the electromagnetic relay type conventionally comprises a field structure including a core provided with a winding, a movable armature carried by the field structure, and a set of switch springs operatively associated with the armature.

It is an object of the present invention to provide an improved switching device of the type described which is of rugged and economical construction and which is reliable and positive in operation.

Another object of the invention is to provide in a switching device an improved multicontact switch spring arrangement which positively insures electrical contact between each pair of associated contacts carried by the switch springs and which accommodates equalization of the contact pressure among the pairs of associated contacts.

In brief, the objects set forth above are in part realized in accordance with one feature of the present invention by providing a switching device which comprises a pair of associated switch springs, each of the switch springs being provided with two spaced-apart and independently flexible portions and a plurality of contacts respectively carried by the flexible portions of the switch springs, the contacts respectively carried by the flexible portions of one of the switch springs respectively cooperating with the contacts respectively carried by the flexible portions of the other of the switch springs. Also, means is provided for moving one of the switch springs, thereby to effect a change in the relative positions of the contacts respectively carried by the flexible portions of the switch springs. More particularly, each of the switch springs is formed of flat metallic stock and is provided with a base end and a free end; and a cantilever mounting is provided at the base end of each of the switch springs, the base ends of the switch springs being insulated from each other.

The two independently flexible portions provided on one of switch springs are formed by an elongated slot provided in the one switch spring adjacent the free end thereof. Also, the contacts respectively carried by the flexible portions of the one switch spring are carried thereby substantially at the points along the lengths of the flexible portions of the one switch spring whereat the flexible portions have a maximum movement with respect to the base portion of

the one switch spring, thereby to insure self-equalization of contact pressure between the respective engaging contacts when the contacts carried by the flexible portions of the one switch spring are respectively forced into engagement with the contacts respectively carried by the flexible portions of the associated switch spring. Furthermore, the means for moving the one switch spring comprises an operating member carried by the one switch spring adjacent the free end and intermediate the two flexible portions thereof and an element operative to engage the operating member.

In accordance with another feature of the invention, the operating member is secured to the one switch spring adjacent the free end and intermediate the two flexible portions thereof by a drive screw extending through aligned openings respectively provided in the free end of the one switch spring and the operating member. Also, the operating member is subjected to some wear incident to the operation thereof by the associated element, whereby dust wearing from the operating member accumulates upon the cooperating metallic contacts. The material of the operating member comprises an inactive organic substance, whereby the dust wearing therefrom and accumulating upon the cooperating metallic contacts does not react with the metallic contacts to provide electrical insulating compounds upon the outer surfaces of the metallic contacts. More specifically, the material of the operating member comprises an inactive organic acetate, such, for example, as a suitable cellulose acetate.

The arrangement for operating the switching device comprises an electromagnetic relay including first and second longitudinally extending field elements arranged in spaced-apart relationship, a laterally extending pivot pin carried by the first field element, means including a clamping member secured to the first field element and embracing a portion of the pivot pin disposed intermediate the ends thereof for clamping the pivot pin directly to the outer surface of the first field element adjacent the end thereof, and an armature operatively associated with the first and second field elements. The armature is provided with two laterally extending arms disposed on opposite sides of the first field element and pivotally mounted on the opposite ends of the pivot pin. The field elements and the armature are so constructed and arranged that the air gap between the first field element and the armature is substantially unal-

tered as the air gap between the second field element and the armature is altered incident to the operation of the relay. More particularly, the armature comprises an operating arm projecting over the outer surface of the first field element and cooperating with the pair of associated switch springs; and the clamping member is formed of nonmagnetic material. A portion of the clamping member is disposed between the first field element and the operating arm of the armature in order to prevent the operating arm of the armature and the first field element from sticking together due to the magnetic forces therebetween.

The novel features believed to be characteristic of the invention are set forth with particularity in the appended claims. The invention, both as to its organization and method of operation, together with further objects and advantages thereof, will best be understood by reference to the following specification taken in connection with the accompanying drawing, in which Figure 1 is a plan view of a switching device of the electromagnetic type constructed and arranged in accordance with the present invention, and a support therefor; Fig. 2 is an exploded side elevational view of the switching device and support shown in Fig. 1, and an enclosing casing therefor; Fig. 3 is an end elevational view of the switching device shown in Fig. 1, and a vertical sectional view of the enclosing casing therefor; Fig. 4 is an enlarged fragmentary longitudinal sectional view of a portion of the switching device taken along the line 4-4 in Fig. 1, illustrating the mounting arrangement for the armature thereof; Fig. 5 is an enlarged fragmentary plan view of a pair of the switch springs included in the switching device shown in Fig. 1; and Fig. 6 is a longitudinal sectional view of the pair of switch springs taken along the line 6-6 in Fig. 5.

Referring now more particularly to Figs. 1 to 3, inclusive, of the drawing, the switching device there shown comprises an insulating support 10 and an electromagnetic relay 11. The relay 11 is provided with a field structure including a longitudinally extending core element 12 provided with a winding 13, a longitudinally extending field element 14, and a movable armature 15 operatively associated with the core element 12 and the field element 14.

As best shown in Figs. 1 and 4, the core element 12 and the field element 14 are arranged in spaced-apart relationship; and the armature 15 is carried by the field element 14 adjacent the outer end thereof. More particularly, the armature 15 is pivotally mounted on the outer end of the field element 14 and is provided with two laterally spaced-apart operating arms 16 and 17 projecting over the outer surface of the field element 14 and two upwardly extending and laterally spaced-apart supporting arms 18 and 19 disposed on opposite sides of the field element 14 and pivotally mounted on the opposite ends of a laterally extending pivot pin 20 carried by the field element 14 adjacent the end thereof. The pivot pin 20 is clamped directly to the outer surface of the field element 14 by an arrangement including a clamping member 21 provided with two spaced-apart clamping arms 22 and 23 embracing a portion of the pivot pin 20 disposed intermediate the ends thereof. The clamping member 21 is securely fastened to the outer surface of the field element 14 by an arrangement comprising a washer 24 and a screw 25, the screw 25 extending

through aligned openings provided in the washer 24 and the clamping member 21 and in threaded engagement with a tapped hole provided in the field element 14.

- 6 First and second sets of associated switch springs 26 and 27, respectively, are carried by the field element 14 and operatively associated with the operating arms 16 and 17, respectively, of the armature 15. The sets of switch springs 26 and 10 27 bias the armature 15 in a clockwise direction about the pivot pin 20, as viewed in Fig. 2, into a normal position. When the winding 13 carried by the core element 12 is energized, the electromagnetic flux set up in the core element 12, the 15 field element 14 and the armature 15 causes the armature to be rotated in a counterclockwise direction about the pivot pin 20, as viewed in Fig. 2, from its normal position to an operated position, thereby to cause the operating arms 16 and 17 20 of the armature 15 to actuate the sets of switch springs 26 and 27, respectively.

The pivotal mounting for the armature 15 closely adjacent both the outer surface and the end of the field element 14 provides a field structure for the relay 11 having a minimum electromagnetic reluctance. More specifically, the core element 12, the field element 14 and the armature 15 are so constructed and arranged that the air gap between the armature 15 and the end of 25 the field element 14 is substantially unaltered as the air gap between the end of the core element 12 and the armature 15 is altered incident to the operation of the relay.

An arrangement is provided for preventing the 30 armature 15 from sticking to the end of the core element 12 due to the residual magnetic forces therebetween, which comprises an adjustable screw 28 arranged in a threaded hole provided in the armature 15 adjacent the end of the core element 12, the screw 28 being formed of a non-magnetic material, such as brass. Furthermore, a locking nut 29 is arranged in threaded engagement with the screw 28 in order to lock the screw 28 in any desired adjusted position. Also, an 35 arrangement is provided for preventing the ends of the operating arms 16 and 17 of the armature 15 from sticking to the adjacent portions of the outer surface of the field element 14 due to the residual electromagnetic forces therebetween, which comprises two portions 30 and 31 of the 40 clamping member 21, the portion 30 of the clamping member 21 being disposed between the operating arm 16 of the armature 15 and the adjacent portion of the outer surface of the field element 14; and the portion 31 of the clamping member 50 45 55 60 65 70 75 80 85 90 95 100 105 110 115 120 125 130 dividual switch springs 34, 35, 36 and 37 arranged in superimposed relationship. Each of the switch springs comprises a base end and a free end, and is provided with a cantilever mounting at its base end. Also, the switch springs are insulated from each other and from the field element 14 at their base ends. The arrangement for mounting and for insulating the base ends of the set of switch springs 26 comprises a base plate 38 carried by the field element 14, a clamping plate 39 and a plurality of insulating strips 40 disposed between the base plate 38, the clamping plate 39 and the switch springs 32 and 33. Also, two screws 41 are provided which extend through aligned openings provided in the base plate 38, the clamping plate 39, the insulating strips 40 and the switch springs 32 and 33 and threaded into tapped holes provided in the field element 14. The arrangement for mounting and for insulating the base ends of the set of switch springs 27 is substantially identical to the arrangement for mounting and for insulating the base ends of the set of switch springs 26 and includes a clamping member 42, two screws 43, a base plate, not shown, carried by the field element 14, and a number of interposed insulating strips, not shown.

Each of the switch springs 32, 34 and 36 comprises a first switch spring; while each of the switch springs 33, 35 and 37 comprises a second switch spring. The first switch springs are of identical construction; and the second switch springs are of identical construction; while the construction of each of the first switch springs is substantially similar to the construction of each of the second switch springs. For example, the first switch spring 32, as best shown in Figs. 5 and 6, has an elongated longitudinally extending slot or eyelet 44 formed therein adjacent the free end thereof which provides the first switch spring 32 with two elongated laterally spaced-apart and independently flexible portions 45 and 46 connected together at the free end of the first switch spring 32 by a curved operating portion 47; while the second switch spring 33 has an elongated longitudinally extending slot 48 formed therein adjacent the free end thereof which provides the second switch spring 33 with two elongated laterally spaced-apart and independently flexible portions 49 and 50. Accordingly, the first switch spring 32 has an elongated eyelet formed therein adjacent the free end thereof; while the second switch spring 33 has a substantially Y-shaped configuration. The second switch spring 33 is arranged in superimposed relationship with respect to the first switch spring 32, the flexible portions 49 and 50 of the second switch spring 33 being respectively superimposed with respect to the flexible portions 45 and 46 of the first switch spring 32.

The flexible portions 45 and 46 of the first switch spring 32 carry two longitudinally extending metallic contacts 51 and 52, respectively; while the flexible portions 49 and 50 of the second switch spring 33 carry two laterally extending metallic contacts 53 and 54, respectively. The metallic contacts 51 and 53 are arranged in cooperating relationship; while the metallic contacts 52 and 54 are arranged in cooperating relationship. More particularly, each of the sets of metallic contacts 51, 53 and 52, 54 are arranged in crossing relationship, thereby to insure proper contact between the cooperating pairs of contacts in spite of slight mechanical variations in the positions of the first and second switch

springs 32 and 33, respectively. Each of the metallic contacts 51 to 54, inclusive, is formed of a precious arc-resisting metal, has a substantially obelisk configuration, and is welded to the associated flexible portion of the switch spring. More particularly, each of the metallic contacts 51 to 54, inclusive, is carried substantially at the point along the length of the associated flexible portion of the switch spring whereat the flexible portion has a maximum movement with respect to the base end or body portion of the switch spring, thereby to insure self-equalization of contact pressure between the respective engaging contacts when the contacts respectively carried by the flexible portions of the first switch spring 32 are forced into respective engagements with the contacts respectively carried by the flexible portions of the second switch spring 33.

In order to facilitate movement of the first switch springs 32, 34 and 36 with respect to the respectively associated second switch springs 33, 35 and 37, operating members 55, 56 and 57 are respectively carried by the first switch springs 32, 34 and 36 adjacent the free ends thereof. More specifically, the operating member 55 is secured to the operating portion 47 of the first switch spring 32 by an arrangement comprising a drive screw 58 extending through aligned openings provided in the operating portion 47 of the first switch spring 32 and in the operating member 55. Preferably, the drive screw 58 is of the Parker-Kalon type; while the operating member 55 is formed of an inactive organic insulating material, for a purpose more fully described subsequently. Furthermore, the operating member 55 is provided with a semispherical operating end. Also, it is noted that the operating members 56 and 57 are substantially identical to the operating member 55 and are respectively secured to the first switch springs 34 and 36 in a manner identical to that in which the operating member 55 is secured to the first switch spring 32.

Referring more particularly to Fig. 3, it will be noted that the operating end of the operating member 55 carried by the first switch spring 32 is arranged in direct engaging relationship with the operating arm 16 of the armature 15; the operating end of the operating member 56 carried by the first switch spring 34 is arranged in direct engaging relationship with the operating arm 17 of the armature 15; and the operating end of the operating member 57 carried by the first switch spring 36 is arranged in direct engaging relationship with the head of the driving screw retaining the operating member 56 to the first switch spring 34.

During the operation of the relay 11, when the winding 13 is energized, the armature 15 is rotated about the pivot pin 20 in a counterclockwise direction, as viewed in Fig. 2, as previously noted, thereby to cause the armature 15 to be moved from its normal position to its operated position. When the armature 15 is moved from its normal position to its operated position, the arm 16 carried thereby engages the operating member 55, thereby to cause the first switch spring 32 to be bent toward the cooperating second switch spring 33; while the arm 17 carried thereby engages the operating member 56, thereby to cause the first switch spring 34 to be bent toward the second switch spring 35. Also, the movement of the operating member 56 carried by the first switch spring 34 is transmitted to the operating member 57 carried by the first switch spring 36, thereby to cause the first switch

spring 36 to be bent toward the cooperating second switch spring 37. More particularly, the two pairs of metallic contacts carried by the switch springs 32, 33 are moved into engagement; and the two pairs of metallic contacts respectively carried by the switch springs 34, 35 and 36, 37 are moved into engagement.

Incident to the operation of the sets of switch springs 26 and 27 by the relay 11, the operating members 55, 56 and 57 are subjected to some wear, whereby dust wearing from the operating members accumulates upon the cooperating metallic contacts carried by the switch springs. In conventional switching devices of this character, the operating members 55, 56 and 57 are formed of hard rubber which contains some sulphur. The sulphur contained in the dust accumulating upon the cooperating metallic contact members carried by the switch springs reacts with the metallic contacts to produce certain metallic electrical insulating compounds of the sulphide type upon the outer surfaces of the metallic contacts, which metallic electrical insulating compounds disposed upon the outer surfaces of the cooperating metallic contacts prevent proper electrical contact therebetween. In order to obviate this inherent defect in conventional switching devices of this type, the operating members 55, 56 and 57 are formed of an inactive organic material in accordance with a feature of the present invention, whereby the dust wearing therefrom and accumulating upon the cooperating metallic contacts carried by the switch springs does not react with the metallic contacts to produce metallic electrical insulating compounds upon the outer surfaces of the metallic contacts. For example, the operating members 55, 56 and 57 may be formed of a suitable phenol formaldehyde or cellulose ester resin. However, it is preferable that these operating members are formed of the cellulose acetate compound known as "Tenite."

The relay 11 and the sets of switch springs 26 and 27 carried thereby are provided with an elongated casing 59 which cooperates with the support 10 to enclose the relay 11 and the sets of switch springs 26 and 27. More particularly, the enclosing casing 59 is provided with a handle 60 and an open end 61 and is slidably carried by the relay 11. The arrangement for slidably supporting the casing 59 upon the relay 11 comprises a guide member 62 carried by the relay 11 and disposed between the field element 14 and the sets of switch springs 26 and 27. More particularly, the screws 41 and 43 which are utilized to secure the sets of switch springs 26 and 27, respectively, to the field element 14 also extend through aligned openings provided in the guide member 62, thereby securely to retain the guide member in position. The guide member 62 is provided with longitudinally extending and laterally projecting guiding beads 63 and 64 disposed on opposite sides thereof adjacent the opposite sides of the field element 14, which guiding beads cooperate with two aligned guiding beads 65 and 66 provided in the opposite side walls of the casing 59. Also, the guide member 62 carries two laterally and downwardly extending locking tabs 67 and 68 on the opposite sides thereof which cooperate with two locking beads 69 and 70, respectively, provided in the opposite side walls of the casing 59. The arrangement of the guiding beads 63 and 64 and the locking tabs 67 and 68 carried by the guide member 62; and the arrangement of the guiding beads 65 and 66

and the locking beads 69 and 70 provided in the opposite side walls of the casing 59 provide for ready placement and removal of the casing 59. Furthermore, it is noted that the interfitting guiding parts carried by the guide member 62 and provided in the opposite side walls of the casing 59 facilitate the sliding movement of the casing 59 and securely lock the casing 59 in position when it is placed upon the relay 11.

It is noted that any reasonable number of individual switch springs may be included in the sets of switch springs 26 and 27 carried by the field element 14 of the relay 11 and that during assembly of the switch springs carried by the field element 14, a suitable number of first and second switch springs are selected and arranged in stacked relationship upon the guide member 62 carried by the field element 14. The stacked switch springs carried by the field element 14 are aligned by a suitable jig and then securely clamped to the field element 14, the alignment of the switch springs by the jig being facilitated by virtue of the fact that the slots provided in the switch springs are normally disposed in alignment with each other, thereby to accommodate the jig. Preferably, the side walls of the jig are tapered toward the forward edge thereof, thereby to insure that the stacked switch springs are aligned both in a lateral and in a longitudinal direction. After the sets of switch springs 26 and 27 have been assembled upon the relay 11, the relay 11 and the sets of switch springs 26 and 27 carried thereby are suitably secured upon the insulating support 10, the support 10 being provided with openings therein through which the terminals for the winding 13 of the relay 11 and for the individual switch springs extend. The casing 59 is then slidably placed upon the relay 11, the casing being guided in place by the guide member 62. When the casing 59 occupies its normal position upon the relay 11 it cooperates with the support 10 to provide an enclosing casing for the relay 11 and the sets of switch springs 26 and 27 carried thereby, in order to prevent the accumulation of dust and other foreign matter upon the cooperating sets of metallic contacts carried by the sets of switch springs.

In view of the foregoing, it is apparent that an improved switching device of the electromagnetic relay type is provided which is of rugged and economical construction and which is reliable and positive in operation.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. In a switching device, a number of switch springs formed of flat metallic stock and disposed with their flat sides opposite each other in substantially parallel planes, each of said switch springs having a base end and a free end, means for providing each of said switch springs with a cantilever mounting at its base end and for insulating said switch springs from each other at their base ends, each of said switch springs being provided with two spaced-apart and independently flexible portions disposed adjacent the free end thereof, a plurality of contacts respectively carried by the flexible portions of said switch springs, the contacts respectively carried by the flexible portions of each of said switch springs respective-

ly cooperating with the contacts respectively carried by the flexible portions of adjacent ones of the switch springs, at least one of said switch springs being provided with an operating portion at the free end thereof extending between the two flexible portions thereof, an operating member carried by the operating portion of said one switch spring substantially intermediate the two flexible portions thereof, and means cooperating with said operating member for bending said one switch spring, thereby to effect a change in the relative positions of the contacts respectively carried by the flexible portions of at least two adjacent ones of said switch springs, said member having a semibulbous operating surface in order to facilitate both lateral and longitudinal flexing of said one switch spring.

2. In a switching device, a pair of associated switch springs, each of said switch springs being provided with two spaced-apart and independently flexible portions disposed adjacent the free end thereof, a plurality of contacts respectively carried by the flexible portions of said switch springs, the contacts respectively carried by the flexible portions of one of said switch springs respectively cooperating with the contacts respectively carried by the flexible portions of the other of said switch springs, at least one of said switch springs being provided with an operating portion at the free end thereof extending between the two flexible portions thereof, an operating member carried by the operating portion of said one switch spring substantially intermediate the two flexible portions thereof, and means cooperating with said operating member for bending said one switch spring toward the other, thereby to force the contacts respectively carried by the flexible portion of said one switch spring into respective engagements with the contacts respectively carried by the flexible portions of the other of said switch springs, each of the contacts being carried substantially at the point along the length of the associated flexible portion of the switch spring whereat the flexible portion has a maximum movement with respect to the body portion of the switch spring, thereby to insure self-equalization of contact pressure among the respective engaging contacts.

3. In a switching device, first and second associated switch springs, said first switch spring including a base end and a free end and having an elongated eyelet provided therein forming two elongated spaced-apart and independently flexible portions and a connecting portion disposed at the free end thereof, said second switch spring including a base end and a free end, means for providing each of said switch springs with a mounting at its base end and for insulating said switch springs from each other at their base ends, two contacts respectively carried by the flexible portions of said first switch spring, two contacts carried by said second switch spring adjacent the free end thereof, the two contacts respectively carried by the flexible portions of said first switch spring respectively cooperating with the two contacts carried by said second switch spring, an operating member carried by the connecting portion of said first switch spring intermediate the two flexible portions thereof, and means for moving said operating member thereby to bend said first switch spring in order to effect a change in the relative positions of the two contacts respectively carried by the flexible portions of said first switch spring and the two contacts carried by said second switch spring, said member having a semi-

bulbous operating surface in order to facilitate both lateral and longitudinal flexing of said first switch spring.

4. In a switching device, first and second associated switch springs, said first switch spring including a base end and a free end and having an elongated eyelet provided therein forming two elongated spaced-apart and independently flexible portions and a connecting portion disposed at the free end thereof, said second switch spring including a base end and a free end, means for providing each of said switch springs with a mounting at its base end and for insulating said switch springs from each other at their base ends, two contacts respectively carried by the flexible portions of said first switch spring, two contacts carried by said second switch spring adjacent the free end thereof, the two contacts respectively carried by the flexible portions of said first switch spring respectively cooperating with the two contacts carried by said second switch spring, an operating member carried by the connecting portion of said first switch spring intermediate the two flexible portions thereof, said operating member being provided with a head having a substantially semispherical configuration, an element operative to engage the head of said operating member, thereby to bend said first switch spring in order to move the two contacts respectively carried by the flexible portions of said first switch spring into respective engagements with the two contacts carried by said second switch spring, the semi-spherical configuration of the head of said operating member accommodating self-equalization of the contact pressures between the respective engaging contacts, and means for operating said element.

5. In a switching device, an operating contact spring having a free end and a stationary base end, means for rigidly securing said base end, diverging portions and converging portions of said spring forming a closed ovate-lanceolate slot near its free end, contacts on said diverging portions intermediate said base and free ends, and an operating member secured to the extreme free end of said spring at the converging point of said converging portions.

6. In a switching device, an operating contact spring having a free end and a stationary base end, means for rigidly securing said base end, diverging portions and converging portions of said spring forming a closed ovate-lanceolate slot near its free end, contacts on said diverging portions intermediate said base and free ends, and an operating member secured to said spring on the longitudinal center line of said spring.

7. In a switching device, an operating contact spring having a free end and a stationary base end, means for rigidly securing said base end, said spring having a closed elongated hole thereby forming two flexible portions near its free end, a contact on each of said flexible portions located on opposite sides of said hole and intermediate the base and free ends, and an operating member secured to said spring on the longitudinal center line of said spring.

8. In a switching device, an operating contact spring having a free end and a stationary base end, means for rigidly securing said base end, said spring having a closed elongated hole thereby forming two flexible portions near its free end, a contact on each of said flexible portions located on opposite sides of said hole and intermediate the base and free ends, and an operating member secured to the extreme free end of said spring on

the longitudinal center line of said spring, said member having a semibulbous operating surface in order to facilitate both lateral and longitudinal flexing of said spring, whereby self-equalization of contact pressure between said contacts is insured.

9. In a switching device, an operating contact spring having a free end and a stationary base end, means for rigidly securing said base end, said spring having a closed elongated hole thereby forming two flexible portions near its free end, a contact on each of said flexible portions located on opposite sides of said hole and intermediate the base and free ends, an operating member secured to said spring on the longitudinal center line of said spring, and other contact springs having contacts for cooperating with said operating spring contacts.

10. In a switching device, an operating contact spring having a free end and a stationary base end, means for rigidly securing said base end, said spring having a closed ovate hole near its free end thereby forming two flexible portions near its free end, a contact on each flexible portion located opposite the widest portion of said

5 hole and intermediate the free and base ends whereby said contacts are located on said spring at the most flexible point, and an operating member secured to said spring on the longitudinal center line of said spring thereby ensuring movement of one flexible portion and its contact in case the other flexible portion and its contact is held against movement.

11. In a switching device, an operating contact 10 spring having a free end and a stationary base end, means for rigidly securing said base end, said spring having a closed ovate hole near its free end thereby forming two flexible portions near its free end, a contact on each flexible portion located opposite the widest portion of said hole and intermediate the free and base ends whereby said contacts are located on said spring at the most flexible point, and an operating member 15 so shaped and secured to said spring on the longitudinal center line of said spring as to ensure the closure of the contact on one flexible portion with a mating contact even though movement of the contact on the other flexible portion is retarded or prevented.
